UNITED STATES PATENT OFFICE.

CHRISTIAN SEIDEL, OF NEW YORK, N. Y., ASSIGNOR TO J. HENRY PETERS COMPANY, OF SAME PLACE.

DESIGN FOR A SKIRT-BINDING.

SPECIFICATION forming part of Design No. 34,297, dated March 26, 1901.

Application filed February 26, 1901. Serial No. 48,998. Term of patent 7 years.

To all whom it may concern:

Be it known that I, CHRISTIAN SEIDEL, a citizen of the United States, and a resident of the borough of Manhattan, in the city and State of New York, have invented and produced a new and original Design for a Skirt-Binding, of which the following is a specification.

The essential features of my design consist in a skirt-binding having a brush pendent from one edge, a series of short columns on the head in proximity to the brush, longitudinal cords, one group arranged on the head in proximity to the said line of short columns and another group of longitudinal cords spaced therefrom, the space between the groups of longitudinal cords presenting a mottled appearance and the space above the upper line of cords presenting a series of short spaced columns.

In the accompanying drawing, which rep-

resents a view of a piece of the skirt-binding, *a* represents the brush; *b*, the line of short columns in proximity thereto; *c*, the lower group of longitudinal cords; *d*, the upper group of longitudinal cords; *e*, the mottled space between the groups of longitudinal cords, and *f* the series of short spaced columns in proximity to the margin of the head opposite the brush.

What I claim is—

The design for a skirt-binding, substantially as herein shown and described.

In testimony that I claim the foregoing as my invention I have signed my name, in presence of two witnesses, this 20th day of February, 1901.

CHRISTIAN SEIDEL.
